L. COHEN

VARIABLE CONDENSER

Filed June 5, 1922

Inventor
LOUIS COHEN

Robert H. Young
Attorney

UNITED STATES PATENT OFFICE.

LOUIS COHEN, OF WASHINGTON, DISTRICT OF COLUMBIA.

VARIABLE CONDENSER.

Application filed June 5, 1922. Serial No. 565,920.

To all whom it may concern:

Be it known that I, LOUIS COHEN, a citizen of the United States, residing at 1656 Euclid Street NW, Washington, D. C., have 5 invented certain new and useful Improvements in Variable Condensers, of which the following is a specification.

This invention relates to variable condensers in general and more particularly to 10 an improved means for adjusting the movable plates of variable condensers.

The object of my invention is to provide 15 a variable condenser of small dimensions and capable of a wide range of capacity variation.

Another object is to provide a variable condenser which is rugged in construction, reliable in operation, and which will eliminate any possibility of short circuits which 20 danger is frequently encountered in the usual type of variable condenser.

Other objects and advantages will appear in the description in the specification.

The above objects and advantages have 25 been accomplished by the device shown in the accompanying drawings.

Figure 1 is a side view of the variable condenser;

Figure 2 is a sectional view of the condenser;

Figure 3 is a plan view of the condenser.

Referring more particularly to the drawings, the device consists of a plurality of fixed plates 1 and movable plates 2. A thin 35 sheet of insulating material 3, preferably composed of mica, is arranged on each movable plate 2. The fixed plates 1 are mounted stationary on supporting members 4 of the casing 5. These supports 4 may all be metal but preferably one only, the remainder being composed of insulating material, the metal support connecting all the fixed plates electrically in parallel.

A centrally disposed partially screw-threaded shaft 6 is arranged in the casing 5, the lower end of the shaft 6 being free to turn in the bearing member 26, a bushing 9 forming the bearing for the upper part of the shaft.

50 An interiorly screw-threaded sleeve 7 is mounted on the shaft 6 in such a manner that as the shaft is rotated the sleeve is raised or lowered thereby, depending upon the direction of rotation of the shaft. A plurality of plates 2 are fixedly mounted on

the sleeve 7 and are arranged alternately with relation to the stationary plates 1.

In order to limit the travel of the sleeve 7 on the shaft 6 a stop lug or disc or the like 19 is fixed on the shaft 6, limiting such 60 travel by abutting against the upper extremity of the sleeve 7.

A suitable gear 10 is fixed on the shaft 6 and meshes with a corresponding gear 13. Gear 13 is fixed on a spindle 22 which is 65 rotatably mounted in the casing top plate 24 and carries a gear 12 which meshes with a corresponding gear 11. Gear 11 is fixed to the sleeve 27 which carries an indicating dial 8. A suitable knob 18 is arranged on 70 the shaft 6 to enable the easy operation thereof.

A lead 15 connects the sleeve 7 to the binding post 16, thereby connecting all the movable plates 2 to said binding post 16. Another binding post 17 is directly connected to the metal support 4 of the fixed plates. 75

The operation of the device in varying the capacity of the condenser is clearly understood. By turning the knob 18 and rotating the shaft 6 a vertical movement of the sleeve 7 is effected, thus moving the plates 2 which are rigidly attached to the sleeve 7. On the upward motion of the sleeve 7, the plates 2 may be brought into close proximity to the corresponding fixed plates, the only separation being the thin insulation material 3 which is preferably of mica sheet, and which can be made as thin as desirable within practical limits. Making these mica 90 sheets very thin the plates are brought together very close and the capacity for each pair of plates may be considerable. The several pairs of plates are connected electrically in multiple, thereby giving a considerable capacity. On the downward motion of the sleeve 7 a stop 19 is provided so that the movable plates 2 are carried downward only to about half the distance between the fixed plates. The distances between adjacent fixed plates may be determined so as to make the capacity, when the plates are separated by half the distance between the fixed plates, extremely 95

small. It is quite obvious that with this arrangement there is no possibility of short circuiting because of the mica insulation between each pair of plates. The gearing arrangements indicated by 10, 11, 12 and 13 are for the purpose of controlling the travel 110

of the dial 8 and they are so proportioned that for the extreme travel of the movable plates the dial 8 rotates only through 180° , which can be graduated in degrees or in any 5 other desired manner which would give an indication of the magnitude of the capacity for any position of the movable plates with respect to the fixed plates. A small gear 10 is mounted on the shaft 6 which engages a 10 large gear 13, this gear 13 is mounted on a shaft 22 and on the same shaft a smaller gear 12 is mounted which engages the larger gear 11, and this large gear 11 is mounted on a sleeve 9 to which is attached the dial 15 8. By this arrangement the rotary motion of the shaft 6 is transferred to the dial 8 and a reduced motion is obtained, the diameters of the gears are so proportioned that if necessary even several revolutions of the 20 shaft 6 will effect only half a revolution of the dial 8, so that for the complete travel of the movable plates 2, the dial 8 travels only one half a revolution.

Figure 3 shows a top view of the condenser in which 23 is an indicated element attached permanently to the case of the condenser, 8 is the dial graduated in degrees, and 18 is the handle for turning the shaft 6. In operation the handle 18 is turned until 30 the desired capacity within the range of the condenser is obtained and is indicated by the point on the dial facing the zero point marked 23. The dial is originally so set that a minimum capacity is indicated by the 35 zero point on the dial.

Claims

1. A variable condenser comprising a plurality of fixed plates, and a plurality of movable plates, said movable plates being mounted 40 on an interiorly screw-threaded sleeve and engaging a threaded shaft, the rotation of said shaft being adapted to reciprocate vertically said movable plates, and thereby effect various desired degrees of separation 45 between said movable and fixed plates of said variable condenser, said stationary plates being provided at their peripheries with spacing and supporting members.
2. In a variable condenser, an outer cylindrical casing, a plurality of stationary and movable plates mounted therein, a centrally disposed interiorly screw-threaded sleeve, a screw-threaded shaft mounted therein and adapted to vertically reciprocate said sleeve, 50 said movable plates being fixedly mounted on said sleeve and movable with said sleeve, said stationary plates being provided at their

peripheries with spacing and supporting members and said movable plates being adapted to be adjusted with relation to said stationary plates for the purpose of varying the capacity of said condenser, said shaft having a stop mounted thereon limiting the movement of said sleeve, a gear mounted on said shaft adapted to mesh with a second gear mounted on a spindle adapted to rotate a third gear, said third gear in turn rotating a fourth gear mounted on a dial-carrying sleeve for the purpose of rotating said indicating dial.

3. In a variable condenser, an outer casting provided with peripherally arranged spacing and supporting members, a plurality of insulated stationary plates mounted thereon, a centrally disposed screw-threaded shaft, an interiorly screw-threaded sleeve mounted thereon and adapted to be vertically actuated by said shaft, said sleeve being adapted to carry a plurality of movable plates, the movement of said sleeve varying the distance between said stationary and said movable plates and thereby varying the capacity of the condenser.

4. In a variable condenser a plurality of stationary plates provided at their peripheries with spacing and supporting members, a plurality of movable plates vertically alternatively arranged, relative therewith, rotary operating means for reciprocating said movable plates and thereby varying their respective distances from the adjacent stationary plates, reduction transmission means connected to said operating means for imparting a less frequent rotation to a capacity indicating dial.

5. In a variable condenser a plurality of stationary plates provided at their peripheries with spacing and supporting members, a plurality of movable plates vertically alternatively arranged relatively therewith, rotary operating means for reciprocating said movable plates, reduction transmission means connected to said operating means for imparting a less frequent rotation to a capacity indicating dial, said rotary operating means consisting of an interiorly screw threaded sleeve adapted to carry said movable plates, and a partially screw-threaded rotary shaft adapted to reciprocate said sleeve.

In testimony whereof I affix my signature.

LOUIS COHEN.
